UNITED STATES PATENT OFFICE.

EMIL J. CARROLL, OF NORWOOD, OHIO, ASSIGNOR TO THE AMERICAN LAUNDRY MACHINERY COMPANY, OF CINCINNATI, OHIO, A CORPORATION OF OHIO.

PADDING.

Application filed September 13, 1923. Serial No. 662,538.

This invention relates to improvements in flat work ironing machines.

- The objects of this invention are to provide an ironing member with resilient means inserted therein, the inserts being of such material as to afford a sufficiently hard surface to effectively engage the work and maintain its form, yet sufficiently resilient to automatically adapt itself to the irregularities in the work; to provide an ironing member with resilient means inserted therein in spaced relation and so arranged as to afford an effective surface for engaging the work; to provide such an ironing member in which inserts of cork or other resilient material are provided, such inserts being arranged in sufficiently close proximity to afford an effective surface for engaging the work; and more particularly to provide an ironing roll in which resilient members are inserted in the surface of the roll body so as to render the same effective and highly efficient in the several particulars above mentioned.
- Further objects of the invention will appear from the following description and claims when considered together with the accompanying drawings.

Fig. 1 is a front elevation, partly broken away, of a single roll flat work ironer embodying my present improvement; Figs. 2 and 3 are sections taken on lines 2—2, 3—3, respectively of Fig. 1; Fig. 4 is a projected plan view of a portion of my improved ironing roll; Fig. 5 is a partial cross sectional view of the ironing roll; Fig. 6 is a partial longitudinal sectional view of the ironing roll; Figs. 7, 8 and 9 are views illustrating the manner of applying the cork inserts to the ironing roll; Fig. 10 illustrates a modified form in a view similar to Fig. 5 and in which coil springs are inserted in the roll instead of corks; Fig. 11 is a partial longitudinal sectional view of a still further modification in which corks are secured to the ironing roll; and Fig. 12 is a view taken on line 12—12 of Fig. 11; Figs. 13 and 14 are partial transverse and longitudinal views of a form in which the cork inserts have dovetail engagement with the roll.

If, in an ironing machine of this type, only flat work like table cloths, napkins, etc. were to be ironed, an ironing roll of hard material which is proof against rusting would be ideal for such a purpose, that is without any cov-

ering whatever. But in order to iron other classes of flat work with seams and buttons and other irregularities, as well as the plain class of work just referred to, the roll has been universally covered, as for instance with 60 layers of burlap, felt, cotton padding and Atlas cloth. Such a covering has been depended upon to accommodate itself to irregularities in the thickness of the work, such as buttons and seams. After a time however, 65 such covering becomes saturated with condensed steam and sooner or later hardens and deteriorates and requires to be renewed. This, of course, involves a great deal of expense and labor as well as loss of time. 70

The present invention, as above briefly outlined, is therefore aimed to improve these conditions by providing the ironing roll with an ironing surface which is sufficiently resilient to accommodate itself to the irregularities in the surface of the work and is free from any tendency to pack down and therefore does not require frequent renewing of the covering as in the old practice. In the form of machine embodying my present improvement as illustrated in Fig. 1 of the drawing, the ironing roll is shown in use with the heated ironing chest 1 and comprises the roll member 2 which is mounted in the frame of the machine for rotation by 85 means of any well known driving mechanism. The roll in this particular case has its outer surface formed with a plurality of recesses 3 which are adapted to receive the small ends of ordinary bottle corks or stoppers 4. These 90 corks are so arranged as to afford spaces therebetween for the passage of moisture and live steam. As illustrated in Figs. 7, 8 and 9, these corks are simply inserted by frictional engagement in the openings 3 and the upper surfaces of the same are then finished off and smoothed down so as to provide an efficient curved ironing surface as illustrated in Fig. 9. Then these inserts may or may not be covered with asbestos cloth which is 95 heat resisting and which when so used forms what might be considered a chamber between the asbestos covering and the roll itself, this chamber or space extending between the corks. The asbestos cloth is used merely 100 to decrease the friction of the roll when running idle. The asbestos cloth extends at its ends so as to cover the ends or heads 5 and 6 of the roll. The head 5 has suitable pipe connections with a suction pump 7, the pipe 110

connections being illustrated at 8, 9, 10, and 11, which last named conduits or connections open through the small apertures 12 into the chamber space between the asbestos covering and the ironing roll. The head 6 is likewise provided with small openings 13 to permit removal of moisture through these passages by means of pump 7. This pump is driven by a suitable motor. The openings 14 in the bottom of the recess 3 permit escape of air upon insertion of the corks.

This form of device has proved highly efficient especially since the use of cork is particularly well adapted for this purpose. 15 Whatever moisture is taken up by the corks has been found to render the same still more resilient than in their dry state and consequently the responsiveness of the corks to the pressure of the roll upon the irregular 20 surfaces of the work is increased and the roll itself considered as a whole is rendered more efficient. Furthermore, the tough character of cork renders such an ironing surface of practically permanent form and its 25 resiliency is equally permanent. It is to be understood that other materials similar to cork may be used in the same manner as here set forth, as for instance, rubber or coil metal springs.

30 Fig. 10 illustrates the use of coil metal springs 15 which are inserted in the same recesses 3 but without the apertures 14 which are of course unnecessary. The upper ends of the springs are first covered with a wire mesh 16 and then with asbestos cloth 17. In this case, as in the case where cork inserts are used, the individual springs are responsive to the local irregularities in the surface of the work with the result that any such small 35 irregularity, as for instance a button on the work, will cause a depression of the spring or cork insert at that particular point and will not affect the rest of the ironing surface. Then, because of the resiliency of the cork 40 and spring inserts, they will immediately return to normal condition when the pressure is relieved.

In Figs. 11 and 12 the corks are of different form and are set down in a depression formed about the outer surface of the roll.

Grooves 18 are provided to receive the corks which are mounted longitudinally upon the rods 19, the ends of these rods being secured in the up-standing flanges 18^a at the ends of the roll. The several series or rings of corks 55 are spaced by means of wires 20 which extend about the roll between the corks. This form of device may be used either with or without an asbestos covering, the surfaces of the corks being finished off so as to take on 60 a general curvature corresponding to that of an ironing roll. The spaces provided between the corks will permit also the removal of steam and moisture in the same manner as illustrated in connection with Fig. 1. 65

In Figs. 13 and 14 the square cork blocks 21 are slid into the dovetail grooves formed in the roll and are given a spaced relation as shown. The spaces 22 are preserved by cutting the cork inserts of proper size and the spaces 23 may be formed by wires or rods 24. The faces of these inserts are curved according to the curvature of the roll.

What I claim is:

1. A padded member for an ironing machine, comprising a hollow metal body provided with a series of closely spaced recesses, and solid, resilient inserts secured in and substantially filling said recesses and projecting outwardly therefrom, the surfaces of the projecting portions of said inserts being in the same general plane and being sufficiently close together to conjointly form a uniformly yielding ironing surface, and a fabric covering therefor. 75 80

2. A padded member for an ironing machine, comprising a hollow metal body provided with a series of closely spaced recesses, and cork inserts having their lower portions compressed and thereby secured in said recesses and their upper portions projecting outwardly therefrom, the surfaces of the projecting portions of said inserts being in the same general plane and being sufficiently close together to conjointly form a uniformly yielding ironing surface, and a fabric covering therefor. 90 95

In testimony whereof I hereby affix my signature.

EMIL J. CARROLL.
